UNITED STATES PATENT OFFICE.

FREDERICK W. COLBY, OF BOSTON, MASSACHUSETTS.

TELEPHONE-INDEX.

1,266,214.

Specification of Letters Patent.

Patented May 14, 1918.

Application filed April 16, 1917. Serial No. 162,358.

To all whom it may concern:

Be it known that I, FREDERICK W. COLBY, a citizen of the United States, residing at Boston, county of Suffolk, and State of Massachusetts, have invented an Improvement in Telephone-Indexes, of which the following description, in connection with the accompanying drawing, is a specification, like characters on the drawing representing like parts.

This invention relates to an improvement in a telephone index.

The purpose of this novel and useful structure is to provide a device which may present in readily accessible form a large amount of information, data, etc., such, for example, as telephonic addresses of named persons and establishments. And, while the particular construction here shown and described is peculiarly adapted for use with a telephone instrument as a call number index, it is to be understood that its uses may be as widely variant as those mentioned in the prior Patent No. 1,171,838, granted to the inventor hereof upon which structure, together with those disclosed in pending applications of the same inventor, Serial Numbers 73,065, filed January 19, 1916, and 94,025, filed April 27, 1916, this invention constitutes an improvement.

The general object is to provide a device of the character referred to which may be inexpensively manufactured and which is durable, efficient and compact.

A more specific object is to provide such a structure with an improved means of fastening the indicia-bearing sheet or strip to the interior rotatable member.

A further object is to provide an improved means for suspending the rotatable member.

Other objects of the invention will more fully appear from the following description and the accompanying drawings and will be pointed out in the annexed claims.

There has been illustrated in the accompanying drawings a selected embodiment for the purpose of illustrating this invention. This embodiment of the present form is adapted for use with the usual type of telephone instrument, but it is to be understood that the invention is not confined to the exact features shown, as various changes may be made within its reasonable scope.

In the drawings,

Figure 1 is a side elevation of a telephone

instrument showing the improved index applied thereto;

Fig. 2 is a longitudinal section through the device;

Fig. 3 is a section on the line 3—3 of Fig. 2;

Fig. 4 is a partial section on the line 4—4 of Fig. 2;

Fig. 5 is a section on the line 5—5 of Fig. 2;

Fig. 6 is a perspective view of the post;

Fig. 7 is a view of the post disk;

Fig. 8 is a perspective view of the underside of the spool cap;

Fig. 9 is a perspective view of the ribbed spool with its co-operating locking member.

This improved device is shown as attached to the conventional telephone instrument including a base 1 and standard 2, and, while this type is shown, it is obvious that it may readily be secured to and used with other forms. It is demountably clamped to the standard 2 by means of a suitable double clamp 3 which at one end embraces the standard and, at its other end, this novel device. The improved device primarily consists of a casing 4 preferably formed of a light sheet metal entailing, from a practical standpoint, the advantages both of great durability and lightness of weight. This casing has a longitudinal slot 5 which extends the length of the casing. Within this slot 5 is passed an indicia-bearing member which is preferably a piece of sheet material such as paper, or a fabric, one end of which is secured to a member rotatably mounted within the casing 4. This rotatable member, which is termed a spool 6, is preferably similarly formed of a light sheet metal material. This construction permits the inexpensive and relatively simple production of these parts by a stamping process. The indicia-bearing member in this embodiment consists of a strip 7 of paper.

In the devices which were the subject-matter of the earlier applications of this inventor, it was found preferable to employ a fabric as the indicia-bearing member for the reason that the welt, which functioned to hold the inner end of the strip of sheet material in the spool, could be more easily formed upon a fabric than upon paper. Herein a novel means of attaching the sheet material to the spool is provided so that more fragile material such as paper may be

employed and the range of usefulness of the device correspondingly increased. To this end, the spool is provided with a longitudinal rib 8 which is preferably formed by inwardly bending a longitudinal portion of the spool. A complementary spool member is provided cooperatively to function with the spool in order securely to retain the end of the indicia-bearing strip of sheet material. This complementary member comprises a tube 9 having a correspondingly formed complementary inwardly turned rib 10 which outwardly presents a groove to receive the spool rib 8. This tube is of such a diameter that it can be removably positioned within the spool 6. The spool has a longitudinal slot 11 while the tube 9 is also provided with a slot 12 which extends from its lower end to a point adjacent its top.

These slots and ribs in the locking tube and spool are so arranged that in assembled form the strip 7 of paper, or other sheet material, enters the slot 11 in the spool, extends partially around the periphery of the tube and enters within the slot 12 in the tube. The section 13 of the paper strip which extends about the periphery of the tube is effectively clamped, within the ribbed depression or groove longitudinally formed in the tube, by the inwardly presented longitudinal rib of the spool. This affords an internesting clamping holding by the spool of the inner end of the strip of paper. This hold, furthermore, is such that liability to tearing or frictional wear is reduced. The two material-clamping complementary ribs of the spool and tube bear an opposed relation, while the slot 11 of the spool 6 and the slot 12 of the tube 9 bear a substantially offset relation—being on opposite sides of the opposed ribs. This construction, as shown in Fig. 9, causes the strip to extend about a portion of the tube periphery. In assembling, the end of the strip of paper is inserted edgewise in the slot 12 so that the upper longitudinal edge contacts with the closed upper end of the slot. The strip is then rolled about the tube so that it covers the groove or depressed rib 10 thereof and extends a short distance therewith. The spool is then slipped over the tube, the strip entering the slot 11 of the spool. Preferably, as shown in Fig. 9, the rib 8 of the spool does not extend to the lower edge of the spool, *i. e.* this edge portion preserves its normal curvature. This construction functions to aid in the initial sliding of the spool over the tube when the opposed rib of the spool and groove of the tube fit into each other and function to clamp the strip and to hold it against movement. While the ribs thus clamp the strip, it is found that a more retentive holding of strips of various materials, thicknesses and surface finish is attained by the employment of the

tube slot. When the inner end of the paper is inserted within the longitudinal slot 12 of the locking tube, any pull upon the paper tends to rotate or rock the tube within the spool. This movement is limited by the longitudinal engagement of the rib and groove. When a pull is set up on the paper strip, the tube is slightly rotated and the side of the tube groove nearer the tube slot is pressed against the adjacent side of the spool interior rib with a tension proportioned upon the pulling force exerted upon the paper. Hence, a more positive and efficient locking function is achieved. This tube slot also greatly facilitates the positioning of the strip about the tube and results in a practical saving in labor costs in assembling the parts of this device in final commercial form. The lower end of the spool is closed by means of a cap which is provided with an annular shoulder 14 snugly fitting the spool. The lower end of the tube rests adjacent the inner face of this cap which functions to form a rest for the annular base of the tube. The central portion of this cap is preferably cut away to reduce the weight of this rotatable spool. The outside diameter of this shouldered cap is such that its peripheral edge forms a smooth running fit with relation to the inside of the casing 4. As the spool is preferably provided with a suspended support, this cap bearing serves to reduce frictional resistance to a modicum.

This sheet-retaining spool is, as stated, rotatably mounted in the casing and is preferably so mounted in suspended position in order to attain smoothness of action and reduction of friction. The spool is so supported within the casing and, further, is placed under suitable tension so that the indicia-bearing strip is normally retained wound about the rotatable spool. The strip may be withdrawn against the tension acting on the spool by means of a suitable grasping means affixed to the outer end of the strip which projects through the slot 5 of the casing. The grasping means is of such size that it may not enter within the casing slot and thus is normally held in accessible position on the casing exterior so that it may easily be pulled to present the strip length to view.

The preferred embodiment of the novel handle here disclosed is provided with a clamping means which retentively holds this outer end of the strip. It is similar in construction and function to the spool and interior tube construction and consists of a cylindrical or tubular handle 15 having a longitudinal slot 16. A tube 17 is adapted to fit closely within the cylindrical handle. This tube is also provided with a longitudinal slot 18 which may receive the outer end portion of the strip. The handle 15 is similarly to the spool 6, provided with

a longitudinal interior rib 19 formed by depressing a longitudinal portion of the preferably sheet metal handle, while the handle tube 17 has a correspondingly formed 5 operating rib 20 which forms an outwardly presented depression or groove to receive slidably the rib 19 of the handle. The strip is inserted, rolled and held in a manner similar to that in which the inner end of 10 the strip is held by the spool and its co-operating locking tube. It may be noted that this mode of securing the strip to the spool and to the grasping means is such that strips may be employed which are not 15 provided with welts, fasteners or clamping means of any type. This is of advantage in that the device may readily be used for the convenient keeping of price lists, announcements and divers advertisements, the 20 strip being ready for use when run off the presses and cut to size. As the portion of the paper, or other strip material, emergent from the handle slot, is subjected to frequent wear and strain, it has been deemed 25 preferable to form the lips 21 on each side of its longitudinal slot 16. This is easily formed by bending back the slot edges and thus providing a substantially flaring opening so that the strip has a smooth surface 30 presented thereto at each slot side.

The spool is rotatably mounted and, while it may be so mounted to rotate in various axial positions with respect to the upright, it is shown as preferably mounted in the 35 latter position, *i. e.*, substantially parallel to the position normally assumed by the telephone instrument to which it may be affixed. As before stated the lower end of the spool is provided with a running guiding fit with 40 relation to the casing interior by means of the annular shoulder 14 of its lower cap. Upon the upper end of the spool is placed a cap 22. This cap preferably supports the spool 6 and its tube 9. The side wall of 45 this cap has a diameter such that it snugly fits over the exterior of the cylindrical spool end. To assure its retention under all conditions of service the side wall of the cap is preferably apertured at two diametrically 50 opposed points and the end portion of the spool is punched outwardly so that the projections 23 may extend within the apertures and prevent the removal of the cap. This cap 22 is also provided with an annular 55 flange 24, the extreme diameter of which is slightly less than the interior diameter of the casing 4 so that a smooth running guiding fit is also afforded at this end of the spool.

60 This spool cap 22 is directly suspended from, and carried by, a novel rotatable member which comprises a post 25. This post is preferably made from a single piece of metal which can be inexpensively stamped 65 out and bent into the desired form. As

shown, it is substantially T-shaped in form and is employed in inverted position, *i. e.*, with the head 26 in lowermost position as shown in Fig. 6. The post is made by bending the metal upon itself to form the head 70 26 and the stems 27 and 28. The stem 28 is preferably made longer than the overlying stem so that its upper end may be bent from the straight dotted line position shown in Fig. 6 into the full line position. 75 This bend portion forms the lap 29 which is inserted in the slot 30 of the disk 31 carried in the spring chamber formed by the casing cap. The post is suspended from this disk, and, because of the angular engagement of the slot 30 and the stem 28, is rotatably carried thereby. As the portion of the post which passes through the disk is not in line with the axial center of the post, the slot 30 of the disk is preferably 80 cut off center so that concentric rotation of the disk and post may be assured. 85

The upper, or supporting, cap 22 of the spool is centrally apertured and radiating therefrom are openings. The metal is 90 turned, as shown in Fig. 8, inwardly to form the integral depending wings 32. The length of the central aperture and the radiating openings formed by the inwardly turned metal is such that the head 26 of 95 the post may be passed therethrough and, upon being turned counter-clockwise as in the underside view in Fig. 8, the outer portions of the head of the post will be engaged by the inner surface of the cap and will 100 abut against the depending wings 32. Thus the spool cap 22 not only functions to support the spool from the post but also to cause the torque set up in the post by a spring means constantly to act upon the 105 spool and thus tend to retain the spool so that the strip is held wound up thereon.

This post is rotatably mounted and held under adjustable tension within the spring chamber formed by the cap 33. Spring tension means are positioned within this chamber to co-operate with the post and thus to govern normally the spool movement. A coiled spring 34 is preferably employed, one end being held in relatively fixed position 110 while the other is secured to the rotatable post of the spool. A simple mode of affixing the relatively stationary end of the spring is afforded by this construction. As disclosed in this preferred embodiment the 115 spring 34 has secured thereto at the outer end, as by a rivet 35, a complementary spring member 36. This complementary member is preferably wider than the spring 120 so that a longitudinal portion may be seated in the annular recess 37 formed in the interior of the cap 33 by turning the circular wall of the cap upon itself. Thus, it 125 may be noted that not only is an annular recess formed but also there is provided a 130

reinforced flange by which the cap so fits the upper end of the casing 4 that it is held against the torque of the spring in operation and yet the cap may be manually 5 turned to increase or decrease the effective spring tension acting upon the post. This complementary spring member is of similar, 10 resilient metal material and the spring end is so secured thereto (see Fig. 2), that, when the member is seated in the annular recess, the lower longitudinal edge of the coiled spring is substantially on the upper face of the base of the cap. The complementary member, when in position, tensionally bears 15 throughout its width against the inner face of the cap and thus is held in constant frictional engagement therewith against any tendency to rotation induced by the torque of the coiled spring.

20 The other, or inner, end of the coiled spring is preferably detachably secured to the post. In this type of post the inner end portion of the spring is passed between the stems 27 and 28 of the post and the temper 25 is removed from the end portion which is bent about one of the stems as shown in Fig. 4. This assures the retentive frictional engagement of the spring by the post. Means are provided in the spring chamber to retain the post in substantially upright position so that it may not assume an angular position with respect to the axis of the spool and hence tend to jam or to create undue frictional resistance to rotation.

30 Such is the function of the novel disk 31 positioned within the spring chamber and by which the spool post is rotatably supported. This disk consists of a circular piece of relatively thin metal and is preferably given a smooth finish on its under surface. This under surface rests upon the upper edges of the coiled spring 34. The lap 29 formed by the turned-over portion 35 of the longer stem 28 of the post is inserted within the oblong slot 30 of the disk.

The diameter of this disk is such that it does not normally contact with the adjacent face of the complementary spring 36 but is retained in substantially horizontal position by contact with the plurality of coils of the spring 34.

The spring chamber is preferably closed by means of a cap 38, the spring-controlled spool is thus rotatably suspended within the 55 casing in such manner that only a modicum of friction is entailed by the moving parts. The annular shoulder 14 of the cap positioned on the lower end of the spool functions as a lower guiding means and may 60 turn freely in the casing.

This lower end of the casing 4 is so protected and reinforced that distortion under working conditions is obviated. These protecting members also function to close the 65 lower end of the slot. They comprise a

flanged cap 39 inserted within the casing end. It is formed to be so positioned by a driving fit and does not contact with the shouldered cap of the spool. This inner cap 39 is formed with an annular flange which, 70 in conjunction with the annular flange of an exteriorly positioned cap 40, co-operatively functions to preserve the inside gage of the casing end.

There is thus provided a device of this 75 type which is inexpensively constructed by means of a few simple operations. The improvements result in added smoothness of operation and ease and rapidity of assemblage, and, due to the novel means for securing the information-bearing strip to the spool and to the handle, it is possible to have a greater range of materials from which the strip may be made.

80 It is to be understood that the construction disclosed herein is illustrative but not restrictive and that the same may be modified within the meaning and scope of the claims which follow.

Having fully described my invention, 85 what I claim as new and desire to secure by Letters Patent is:

1. In a device of the class described, a cylindrical casing having a longitudinal slot, a spring-controlled spool rotatably secured 95 in said casing, a flexible strip extending through said slot and adapted to be wound about said spool, and a complementary member having an internesting rib and groove engagement with said spool to secure the inner end portion of the strip to the spool.

2. In a device of the class described, a cylindrical casing having a longitudinal slot, a spring-controlled spool rotatably secured in said casing, a flexible strip extending through said slot and adapted normally to be wound about the spool, a complementary member to fit slidably within the spool, 105 said spool and member having longitudinal slots bearing an offset relation so that the inner end portion of the strip may enter the spool slot and extending interiorly the spool enter the slot in said member, co-operating means on said spool and member to 110 engage said extension of the strip within the spool and to hold it against release.

3. In a device of the class described, a cylindrical casing, having a longitudinal slot, a flexible strip extending through said slot, a spring-controlled cylindrical spool rotatably secured in said casing and adapted to have the strip normally wound thereabout, a tube-like member slidably to fit within the cylindrical spool, said spool and member having a longitudinal rib and groove engagement and each having a longitudinal slot, said slots being on opposite sides of said engagement so that the inner end of the strip may extend through the 130

spool and member slots and between the rib and groove whereby the strip is securely attached to the spool.

4. In a device of the class described, a cylindrical casing, a flexible strip, a spool adapted to have the strip normally wound thereabout, a disk rotatably supported in said casing, above said spool, means for preventing movement of said disk longitudinally of said casing toward said spool, a rotatable spring-controlled element supported from said disk, and means on said element to support said spool.
5. In a device of the class described, a cylindrical casing, a flexible strip, a rotatable spool adapted to have the strip normally

wound thereabout, a disk rotatably supported in said casing, above said spool, means for preventing movement of said disk longitudinally of said casing toward 20 said spool, a rotatable spring-controlled post having an integral portion bent demountably to engage said disk and be thereby supported and also having an integral head, and means on said spool to engage said head 25 so that the spool may be thereby supported and may have its rotation governed by said spring-controlled post.

In testimony whereof I have signed my name to this specification.

FREDERICK W. COLBY.
